UNITED STATES PATENT OFFICE.

JOHANN G. PETERSON, OF HARTFORD, CONNECTICUT.

SNAP-SWITCH.

1,077,746.

Specification of Letters Patent.

Patented Nov. 4, 1913.

Application filed September 22, 1911. Serial No. 650,744.

To all whom it may concern:

Be it known that I, JOHANN G. PETERSON, a citizen of the United States, residing at Hartford, in the county of Hartford and State of Connecticut, have invented certain new and useful Improvements in Snap-Switches, of which the following is a specification.

This invention relates to snap switches, the object of the invention being to provide a simple and effective device of this character which can be inexpensively made, and the parts of which can be readily and easily assembled.

In the drawings accompanying and forming part of the present specification I have shown in detail one convenient form of embodiment of the invention which to enable those skilled in the art to practise the same will be set forth fully in the following description, while the novelty of the invention will be included in the claims succeeding said description. From such statement it will be clear that I do not restrict myself to such showing. I may depart therefrom in several respects within the scope of my invention defined by the claims following said description.

Referring to said drawings: Figure 1 is a plan view of a base portion and parts attached thereto of a snap switch constructed in accordance with my invention. Fig. 2 is a transverse sectional view on line 2-2 of Fig. 1 showing in addition a dial plate and handle or button. Fig. 3 is a detail sectional view on line 3-3 of Fig. 1. Fig. 4 is a detail sectional view of the dial plate and means for securing the same to the spindle. Figs. 5 and 6 are plan and elevation views respectively of a member hereinafter more fully described.

Like characters refer to like parts throughout the several figures of the drawings.

The switch includes in its make up a supporting body as 2 which may be made of any suitable material such as wood, porcelain or composition, and which is perforated for the passage of the spindle 3 which may be connected with said supporting body in any suitable manner and which as is usual is adapted to be rotated. The upper or inner side of the body 2 has a counterbore 4, and in this counterbore are disposed the ratchet plate 5 and the ratchet 6, both of which operate after the usual fashion. I connect

the ratchet plate and ratchet 6, however, in a novel and advantageous manner as will hereinafter appear. The ratchet plate at suitable points upon its periphery or rim is provided with downwardly turned prongs or barbs 7 which are fitted in holes in the bottom of said counterbore 4. It has been customary to connect the ratchet plate and ratchet by riveting. This is a somewhat expensive procedure and it is not altogether always satisfactory. To eliminate the disadvantages of a riveted union I punch from the ratchet 6 several preferably circular lugs 8, four of which are shown, although this number is not essential. These lugs or ears 8, as will be clear, are integral with the ratchet, and they are in size a little more than half a circle, being punched or otherwise projected into perforations or openings in the ratchet plate 5 so as to rigidly and firmly connect said ratchet plate and ratchet. The spindle 3 is furnished with the customary cam 9 and co-operating locking-plate 10, the latter of which co-acts with the ratchet 6 in the well-known manner, in view of which it is unnecessary for me to describe this action.

The body 2 carries two sets or pairs of binding posts, each of those of one set being denoted in a general way by 11 and each of those of the other set being denoted by 12. The only practical difference between the two sets or pairs of binding posts is in their size. I might also state that the two binding posts 11 are disposed approximately diametrically opposite each other and that the two binding posts 12 are situated in similar relation, all of them being sustained by the body 2. I will describe in detail one of the binding posts 11 which is a duplicate, as will be gathered, of the other. The binding post 11 involves in its organization the plate 13 having oppositely disposed reduced portions 14 and 15, the reduced portion 14 extending downward from the body of said plate, while the reduced portion 15 extends upward from said plate. The downwardly extending reduced portion 14 projects through a slot in the body or web portion of an angular plate 16 which body fits flatwise against the upper or inner surface of the supporting body 2 and is equipped with the downturned lug 17 adapted to extend into said body 2. To rigidly connect the plate 13 with the body of the angular plate 16 said reduced portion 14

after it has been passed through the slot in the body of said plate 16 may have staked therefrom the lugs 18 which, as will be understood, effectually prevent upward dis-
 5 placement of the binding post plate 13, said lugs 18 engaging said plate 16 for such purpose. It will be understood that the supporting body 2 has a cavity or hole to receive this reduced portion or neck 14. Ex-
 10 tending through the supporting body 2 is a screw 19 which is in threaded connection with the body of the angular plate 16. Fitted around the upwardly extending reduced portion 15 are the shanks or butts of the
 15 spring contacts 20 which are separated from each other by a spacing member 21, the upper portion of said reduced extension 15 being headed over the spacing member 21 on the upper or outer spring contact 20,
 20 as at 22. These spring contacts at their inner or active ends are of familiar construction, so that it is not necessary for me to describe the same in detail.
 Tapped through the flange or upstanding portion of the angular plate 16 is a binding screw 23 about which wire is wrapped so as to electrically connect said wire with the binding post 11. The said flange is shown provided at opposite sides of the head
 30 of said screw with lugs 24, and I might say at this point that it is not uncommon to arrange lugs at opposite sides of a screw head, the function of said lugs being to hold said wire in electrical connection with
 35 the screw in case said wire is not coiled properly about the shank of the screw. It has been usual, however, to make these lugs straight and when a wire has been inserted between one lug and the adjacent screw, the
 40 tendency has been to jam the screw against the opposite lug, and it follows that there will be but a single point of contact between said head and said opposite lug, so that the result is to bend the screw or even dislodge
 45 it. The inner surfaces of the lugs 24 are of circular or arcuate form, and this I can secure by curving said lugs, and said surfaces are preferably upon the same or approximately the same radius as the adjacent
 50 screw head, so that when said head is forced against a lug it will find a firm and substantial bearing thereagainst, the lug partially embracing the screw head and thereby effectually resisting motion thereof.
 55 Referring now to the binding posts 12. A detail description of one of these posts, will, of course, apply to the other as they are of similar construction. The binding post 12 comprises a plate 25 of substantially T-
 60 form, the shank of which is passed through a plate 26, the connection between the shank of said plate 25 and 26 being identically like that described in connection with the plates 13 and 16 for which it is unnecessary for me
 65 to repeat such description. The plate 26

is constructed and mounted like, and has the same appliances, as the plate 16, so that I need not further describe the same. Inclosing the shank or body of the T-shaped plate 25 is a spacing member 27 upon which rests the shank of the spring contact 28, while on the spring contact 28 is the upper spacing member 27 surmounted by the shank of the spring contact 28 which also fits around the body of said T-like plate 25, the contacts 28 being exactly like the contacts 20, although nearer to the upper surface of the supporting body 2. I might indicate at this time that the contact springs 20 coöperate with one set of blades, while the contact springs 28 coöperate with another set of blades rotative with the spindle 3, as will hereinafter appear. The upper contact 28 also bears against the head of the T-shaped plate 25.

Resting on the cam 9 is a carrier plate 30 constituting part of a commutator which which will now be described. It is not necessary for me to describe in detail this carrier plate as the same is of common construction in snap switches. Supported by the carrier plate is an insulating body such as a washer 31 which may be of any suitable material such as fiber, and superimposed upon this fibrous insulation is a plate 32 or disk 32 provided with outwardly extending blades 33 which coöperate with the spring contacts 28 already described. Inclosed by the plate 32 is insulation 34 which may be of fibrous material. Supported by the insulating washer 34 and the plate 32 is an insulating washer 35 upon which is mounted the plate 36 inclosing the insulating washer 37, said plate 36 and washer 37 being surmounted by a washer 38, the commutator composed of the two plates and several washers having openings or perforations through which the rotary spindle 3 extends. The upper plate 36 has oppositely disposed approximately right angular blades 39, the outwardly extending branches of which coöperate with the spring contacts 20. It will be understood that when the blades 39 bridge the two sets of spring contacts 20 that said contacts are electrically connected, the blades 33 at this time bridging the contacts 28 situated in a different plane.

The commutator already described in detail is surmounted by a top plate 40 which has downwardly extending lugs 41 projecting through the several plates and washer of the commutator and also through the carrier plate 30, said lugs being upset or headed at 42 at their inner ends so as to rigidly connect the several parts of the commutator. The terminal washers of the commutator have bosses fitting in the holes of the plates of said commutator and through these bosses, the lugs 41 extend, and by reason of

this construction short circuiting by said lugs is avoided. The crown plate 40 is provided on its upper or outer surface with several lugs 43, adapted to be interchangeably engaged by the lower end of the coiled operating spring 44, by reason of which the tension of the spring can be regulated. The upper end of the spring 44 bears against a lug 45 on the dial carrier 46 which supports the dial 47, the two parts being perforated to receive the spindle 3, and said dial and dial carrier being connected together by lugs 48 punched from the dial and extending through slots in the dial carrier. The outer or upper end of the spindle 3 is threaded to receive the button or handle 49 by manipulating which the said spindle may be turned, so that through the intermediate parts, the spring 44 will be tensioned and subsequently released after the usual fashion to move the several contact blades into and out of electrical connection with the coöperating spring contacts. Said handle 49 by reason of its threaded connection with the spindle 3 firmly presses together the dial-carrier 46 and dial 47.

What I claim is:

1. A switch comprising a supporting body, a plate fitted against said body and provided with a down-turned lug, the supporting body having an opening to receive said lug, a screw extending through said body and engaging said plate, a second plate, the first plate having a slot and the second plate extending through said slot and having projections engaging the under surface of the first plate, and contact members carried by the second plate.

2. An electric switch provided with a commutator comprising superimposed plates and insulating washers, a carrier for said commutator, and a crown plate surmounting the commutator, provided with approximately diametrically opposite lugs extending through the plates and washers of the commutator and also through the carrier for holding said commutator parts and carrier in assembled relation.

3. A switch comprising a spindle, a com-

mutator connected with said spindle, a crown plate surrounding said spindle, a dial and a dial carrier also surrounding the spindle, a spring coiled about the spindle, one end of said spring bearing against said dial carrier, said crown plate having several lugs adapted to interchangeably receive the other end of said spring.

4. An electric switch comprising a supporting body, a plate fitted against said body, means for connecting said plate with the supporting body at two different points to prevent rotation thereof, a second plate, the first plate having a slot and the second plate extending through said slot and having projections staked from its side edges, engaging the under surface of the first plate, and contact members carried by the second plate.

5. A switch comprising a supporting body, a plate fitted against said body and provided with a down-turned lug, the supporting body having an opening to receive said lug, a fastening member for connecting the plate with said supporting body, a second approximately flat plate, the first plate having a slot and the second plate extending through said slot, and having projections staked therefrom engaging the under surface of the first plate, the supporting body having an opening to receive the staked portion of the first plate, and contact members carried by the second plate.

6. A switch comprising a supporting body, a plate secured to said body, a second plate, the first plate being slotted and the second plate having a downwardly extending portion snugly fitted in and extending through the slot of the first plate, the second plate having integral projecting means engaging the under surface of the first plate, and contact members carried by the second plate.

In testimony whereof I affix my signature in presence of two witnesses.

JOHANN G. PETERSON.
